UNITED STATES PATENT OFFICE.

CHARLES W. BRAYTON, OF WATERLOO, IOWA, ASSIGNOR TO WATERLOO CEMENT MACHINERY CORPORATION, OF WATERLOO, IOWA, A CORPORATION OF IOWA.

CONCRETE-MIXER OR THE LIKE.

1,182,140.

Specification of Letters Patent.

Patented May 9, 1916.

Application filed December 6, 1913. Serial No. 805,016.

To all whom it may concern:

Be it known that I, CHARLES W. BRAYTON, a citizen of the United States, residing at Waterloo, in the county of Blackhawk and State of Iowa, have invented certain new and useful Improvements in Concrete-Mixers or the like, of which the following is a description.

My invention belongs to that class of devices known as mixers, and relates particularly to that type of mixer known as a single batch mixer, particularly adapted for mixing concrete or the like. It is particularly intended for that type of mixer which is provided with a drum having one end open and suitably rotatably supported, so that it may be continuously driven to mix the concrete, or tilted to discharge the same, and relates particularly to auxiliary supporting means for supporting the drum when in one of these positions, or if desired, both in the mixing or discharging positions.

The invention has among its objects the production of a device of the kind described that is extremely simple, convenient, efficient, durable and satisfactory, and may be employed wherever desired.

To this end my invention consists in the novel construction, arrangement and combination of parts herein shown and described, and more particularly pointed out in the claims.

In the drawings, wherein like reference characters indicate like or corresponding parts, Figure 1 is a side elevation of a portion of a mixing machine, showing my auxiliary support with the drum supported thereby; Fig. 2 is a sectional view taken substantially on line 2, 2 of Fig. 1; Fig. 3 is an end elevation of the mixer shown in Fig. 1, and Fig. 4 is an end elevation of a modified form of the supporting device, arranged to support the drum in either mixing or discharging positions.

Referring to the drawings, the mixer shown is provided with a frame, or what is commonly called skids, consisting of the side bars 1 and cross bars 2, which cross bars form a bolster when the machine is carried on wheels 3 in the well known manner. Mounted on the frame are a pair of standards 4, 4 of any suitable form, which carry a yoke or U-shaped supporting member 5.

The supporting member is preferably pivotally carried from the standards, so that it 55 may be rocked so as to tilt the drum carried thereby. The drum shown comprises a part 6, preferably extended as at 7, and open at the end, the same being mounted upon a shaft 8 carried by the support 5, so that the 60 drum may be rotated on the support. With the type of mixer shown the drum is provided with a flange 9, having teeth adapted to mesh with the driving gear or pinion 10, which is extended through the standard and 65 is driven in any desired manner. In Fig. 1, sprockets 11 and 12, and sprocket chain 13 are shown for driving the pinion 10, 14 being a suitable driving shaft, which may be driven from an internal combustion engine 70 or the like. The rocking of the support 5 may be controlled in any desired manner, handles 15 being shown for the purpose. The particular rocking or tilting mechanism, and locking device therefor, however, is fully de- 75 scribed in a companion application, and need not be described in full herein. It may be mentioned, however, that by grasping the handles 15, the drum may be thrown to the mixing position shown in full in Fig. 3, or 80 to the discharging position shown in the dotted line in the same figure.

It is obvious that a drum supported on a shaft in the manner described throws considerable strain upon the shaft, particularly 85 when the mixer is in mixing position and contains a batch of concrete. This strain on the shaft 8 may bend the shaft, or cause it to crystallize and break, even though the construction of shaft and bearing is well de- 90 signed and substantially made. My preferred form of shaft and bearing need not be described in full herein, as this forms part of a companion application in which it is fully described and claimed. 95

The construction shown for supporting the drum, particularly in its mixing position, is extremely simple, and consists of the two rollers 16, which may be carried from the frame in any desired manner. 100 These rolls are preferably so positioned that they contact with the flange 9, or with the edge of the gear and support a portion of the weight of the drum when the same is thrown to the position indicated by the full 105 lines in Fig. 3. They are made of any suit-

able material, and of any convenient size, and are preferably mounted on or provided with anti-friction rollers or bearings (not shown in detail). In the construction shown, the rolls 16 are rotatably secured on the axles or shafts 17, carried by the brackets 18, secured to the side frame 1. These brackets are preferably connected and braced by the connecting member 19, and by brace members 20, secured to the standards 4. It will be noted that in the preferred construction, the brackets 18, or that is, the ends 18² of the same, extend substantially at right angles to the axis of the shaft 8, which carries the drum, so that the shafts 17 carried by the brackets are substantially parallel with the shaft 8, and there is no binding or excessive friction. When the mixer is thrown to the position for mixing, while a portion of the weight and all the end thrust is carried by the shaft 8 and the support 5, a considerable portion of the weight will be carried by the rolls 16, and to a large extent remove the strain from the shaft 8. 5 The rolls also act as a stop for limiting the movement of the drum when thrown to mixing position, preventing its being thrown far enough to discharge the contents instead of mixing, or straining the handles, and lock. When the batch of concrete is sufficiently mixed, the drum is thrown to the position indicated by the dotted lines, discharging the concrete into wheelbarrows, or wherever desired. 10 In Fig. 4, additional rolls 16¹ are shown, positioned on the shafts 17, so that when the drum is thrown to the discharging position, the flange 9 will rest upon the rolls 16¹, supporting the drum and acting as a stop. In this figure the rolls 16¹ are shown the same size as rolls 16, but they, of course, may be made larger or smaller, as may be desired. 15 While the rolls might be carried by the drum, or associated tilting parts, and be arranged to coöperate with the frame, the construction shown and described is extremely simple, and does not in any way increase the weight of the drum, making it easier to throw or tilt to either position. 20 Having thus described my invention, it is obvious that various immaterial modifications may be made in the same without departing from the spirit of my invention; hence I do not wish to be understood as 25 limiting myself to the exact form, construction, arrangement or combination of parts herein shown and described, or uses mentioned.

What I claim as new and desire to secure by Letters Patent is:—

1. In a device of the kind described, a suitable frame, a rock shaft mounted on the frame, a mixing drum open at one end and closed at the other, rotatably mounted at its base on the rock shaft, whereby the drum may be charged when tilted in one direction, and is tilted in the opposite direction to discharge the same, in combination with a fixed stop provided with a plurality of anti-friction rollers permanently and fixedly positioned in the path of the drum, and limiting its movement as it is rocked to the loading position. 60

2. A device of the kind described, comprising a suitable frame, a rock shaft mounted on the frame, a mixing drum open at one end and closed at the other, rotatably mounted at its closed end upon the rock shaft, whereby it is rocked in one direction to be loaded and rocked in the reverse direction to be discharged, and means for rotating the drum, in combination with a stop provided with anti-friction rollers permanently positioned in the path of the drum, and limiting its movement as it is rocked to the lower position, and an additional stop likewise provided with anti-friction rollers positioned in the path of the drum when it is rocked to the discharging position. 70 80

3. A device of the kind described, comprising a suitable frame having mounted therein a rock shaft, a mixing drum open at one end and closed at the other, rotatably mounted at its closed end on the rock shaft, shaft, whereby it is rocked in one direction for loading, and rocked in the reverse direction for discharging the contents, in combination with suitable brackets carried by the frame provided with two pairs of anti-friction rollers, one pair of said rollers being maintained to limit the rocking movement of the drum in one direction, and support the same while in that position, and the other pair being arranged to similarly limit the rocking movement of the drum in the opposite direction, and support the same while in such position. 90 95 100 105

In testimony whereof, I have hereunto signed my name in the presence of two subscribing witnesses.

CHARLES W. BRAYTON.
